UNITED STATES PATENT OFFICE.

WILLIAM J. HESS, OF FORT WAYNE, INDIANA, ASSIGNOR TO JUVENILE WOOD PRODUCTS COMPANY, A CORPORATION OF INDIANA.

TOILET-SEAT ATTACHMENT.

Application filed August 23, 1926. Serial No. 130,874.

This invention relates to improvements in toilet seat attachments in which a seat for an infant is provided for use in conjunction with the usual toilet seat for an adult.

5 The object of the improvement is to provide an easily attachable seat for a child, to be centered and held upon an adult toilet seat of usual construction, and to provide the child's seat with a folding back and side 10 arms which will be held rigidly in upright position when adjusted for use, and to arrange the arms and back so that the arms will be folded automatically when the back is moved to folded position.

15 These objects are accomplished by the construction illustrated in the accompanying drawings, in which:—

Fig. 1 is a perspective view of a construction embodying the invention; and

20 Fig. 2 is a side elevation showing the invention applied to a toilet seat, which seat is shown in section.

The characters appearing in the description refer to parts shown in the drawings 25 and designated thereon by corresponding characters.

The invention comprises a rectangular seat 1 having an opening 2 therein, the seat being proportioned so that when placed upon 30 a regular toilet seat 3 it will cover the opening 4 therein. From the bottom of the seat 1 project wire loops 5 and 6 that extend into the opening 4 of the seat 3, in a well known manner, to hold the seat 1 centered upon the seat 3. Also, upon the bottom of the 35 seat are provided rubber cushions 7 that bear upon the top of the seat 3 and prevent it from being marred by direct contact of the seat 1.

40 A swinging frame formed of wire is shaped so as to have a central U-shaped portion 8, oppositely disposed offsets 9, and arms 10, the arms being contiguous with the corresponding offsets at the outer ends thereof. The ends of the arms 10 are turned inwardly and project into the sides of the seat 1 at corresponding points spaced from the rear end of the seat, and said frame has 45 pivotal movement respecting the seat. In 50 the U-shaped portion 8 of the frame is inserted a back-rest 11, the frame being partially imbedded in the upper edge and ends of the back-rest, and a brace 12, consisting of a metallic bar, is secured by screws 13

to the back of the rest 11, the upper end 14 55 of the brace being bent so as to project over the top of the rest and the frame imbedded therein and thus secure the rest in the frame.

Upon each offset 9 is mounted an arm-rest 15, there being a notch 16 in its lower 60 face adjacent its rear end for the reception of the offset, and a clip 17 is secured to the bottom of the arm-rest and extends beneath the corresponding offset and into the notch so as to secure the arm upon said offset. 65 Each arm is supported at a point adjacent its forward end by a corresponding swinging arm 18, the upper end of which is bent at right angles and extends into the side of the arm-rest, and the lower end of which 70 is similarly bent and extends into the corresponding side of the seat 1, there being a metallic clip 19 secured to each side of the seat that overlaps the lower end of the swinging arm to secure it in place and limit 75 backward swinging movement thereof. The arms 10 of the swinging frame, and the swinging arms 18 are so disposed in connection with the seat and arm-rests as to maintain parallelism throughout their movement. 80

A pin 20 projects from the rear end of the seat, and the lower end of the brace 12 is slightly outturned and has an opening 21 therein for the reception of the pin when the back-rest is elevated to its position for use, 85 the brace and pin having latch engagement with each other so that the back-rest and frame in which it is supported are thereby sustained in elevated position upon the seat.

In the front end of each arm-rest is secured a screw-eye 22 to which is secured a breast strap 23, there being a snap hook 24 at one end of the strap that forms the connection between the strap and corresponding screw-eye, so that the strap may be detached 90 from one of said arms to admit of freedom 95 in placing an occupant upon the seat.

In utilizing the invention, the back-rest is raised from the seat until the brace 12 is engaged by the pin 20, the arm-rests being 100 raised with the frame and sustained by the swinging arms in elevated position. The clips 19 against which the swinging arms bear when the unfolding operation is completed, and in preventing an excess backward 105 movement of the arm-rests and the frame connected therewith. The seat is then positioned upon the adult seat, with the wire

loops projecting through the opening therein.

When use of the seat is not required the brace is unlatched from the pin and the back-rest together with the frame is swung down upon the top of the seat, the arm-rests being automatically folded through movement of the back frame.

What I claim is:—

- 10 1. A child's seat attachment for a regular toilet seat comprising an apertured supplemental seat to be superimposed upon the regular toilet seat, including means for holding it centered thereon; a swinging frame 15 formed of wire and having a central U-shaped portion, oppositely disposed offsets, and arms contiguous with the offsets respectively at the outer ends thereof, said arms being pivotally connected with said seat at 20 corresponding points spaced from the rear end thereof; a back-rest positioned in the U-shaped portion of said frame, the frame being partially imbedded in the upper edge and ends of the back-rest; a pin projecting 25 from the back-end of said seat; a brace secured to said back-rest, the upper end thereof being bent so as to extend over the top of the back-rest and frame, the lower end of said brace having latch engagement with 30 said pin when the frame is in unfolded position; arm-rests secured respectively adjacent their rear ends to said offsets; a swinging arm in pivotal connection at one of its ends with each arm-rest at a point adjacent the 35 forward end thereof, the opposite end of said arm having pivotal connection with said seat, said swinging arms having parallel relation with said frame; and a clip on each

side of the seat operable to limit movement of the corresponding swinging arm. 40

2. A child's seat attachment for a regular toilet seat comprising an apertured supplemental seat to be superimposed upon the regular toilet seat, including means for holding it centered thereon; a swinging frame 45 having pivotal connection with said seat at points on the sides thereof spaced from its rear end, said frame including a back-rest; a pin projecting from the back end of said seat; a brace rigidly secured at its upper 50 portion to said back-rest, its lower end having latch engagement with said pin whereby the frame is sustained in unfolded position; a pair of arm-rests having pivotal relation at their rear ends respectively with the corresponding sides of said frame, said arm rests including supporting arms in pivotal connection therewith and with said seat; and a clip on each side of the seat operable to 55 limit movement of the corresponding arm. 60

3. A child's seat attachment for a regular toilet seat comprising an apertured supplemental seat to be superimposed upon the regular toilet seat, including means for holding it centered thereon; a folding structure 65 including a back-rest and frame therefor pivoted to the seat, and arm-rests in pivotal connection with the frame and including supporting arms in pivotal connection therewith and with the seat; and a brace member 70 in rigid connection with the folding structure and having latch relation with the seat whereby the folding structure is sustained in unfolded position.

In testimony whereof I affix my signature.
WILLIAM J. HESS.
